WHIRLING DISC TOY

Kenneth E. Beckley, 8204 S. Broadway, Apt. A,
Whittier, Calif. 90606

Filed Aug. 5, 1968, Ser. No. 13,034

Term of patent 14 years

Int. Cl. D21—02

U.S. Cl. D34—15

FIG. 1 is a side elevational view of a whirling disc toy showing my new design, the opposite side being a mirror image of the side shown;

FIG. 2 is a top plan view; and

FIG. 3 is an elevational edge view, the opposite edge being a mirror image of the edge shown.

I claim:

The ornamental design for a whirling disc toy, as shown and described.
